SAFETY CONTROL FOR MACHINES

Nat A. L. Guill, Broadview, and Bror V. Malmberg, Chicago, Ill., assignors to Western Electric Company, Incorporated, New York, N. Y., a corporation of New York

Application December 8, 1948, Serial No. 64,114

1 Claim. (Cl. 175—335)

1

This invention relates to safety controls for machines, and more particularly to an electric two-hand safety control arrangement for material working machines.

An object of this invention is to provide a simple and efficient electric two-hand safety control arrangement for a material working machine which requires both hands of an operator to initiate a single cycle of operation of the machine and whereby a repeat operation of the machine cannot be effected until the operator's hands are removed from the control arrangement and again applied thereto.

In accordance with the above object, the invention contemplates, in one embodiment thereof, as applied to controlling the operation of a conventional type punch press including a well-known type of one-revolution clutch, an electric two-hand clutch trip safety control arrangement.

Specifically, the control arrangement comprises an air cylinder for actuating the clutch trip, the air under pressure to such cylinder being controlled by a solenoid controlled air valve operated through a circuit which includes a pair of double manually actuated push buttons normally in their out positions to allow current to energize an electromagnet for holding a mechanical latch out of holding engagement with a relay contact lever. Upon manual actuation of both push buttons by the use of both hands of the operator, the electromagnet is deenergized, effecting release of the latch and simultaneously therewith the relay is energized to pull its contact lever into position to close a circuit to a time delay relay, either electronic or of a synchronous motor type, which closes a circuit to energize and cause a normally open relay to close the solenoid controlled air valve circuit for a predetermined time interval, whereupon the air valve is opened to permit air under pressure to flow into the air cylinder to actuate the clutch trip and thus initiate a single cycle of operation of the punch press. The arrangement is such that a repeat operating cycle of the punch press cannot be effected until the push buttons are manually released to permit their return to their normal out positions and again manually actuated.

Other objects and advantages of this invention will more fully appear from the following detailed description taken in conjunction with the accompanying drawing, in which

Fig. 1 is a side elevational view of a material working machine having an electric two-hand safety control arrangement embodying the features of the invention applied thereto; and

Fig. 2 is a diagrammatic view illustrating an electric circuit for controlling the actuation of the air valve and cylinder for actuating the clutch trip of the material working machine.

2

Referring now to the drawing, it will be noted that the material working machine selected to illustrate the invention is a punch press, indicated generally at 10, and including the conventional driving means (not shown) for rotating the usual crank drive shaft upon which a flywheel 11 is mounted. The conventional clutch mechanism is indicated in outline at 12 and is of the one-revolution type, normally in its inoperative position, with the flywheel unclutched from the crank drive shaft. An operation of the clutch 12 is effected through the downward movement of a pull rod 13 operatively connected at its upper end in a suitable manner (not shown) to the trip operating portions of the clutch, its lower end being adjustably connected at 16 to a piston rod 19 of an air cylinder unit 20, the latter being supported by a bracket 24 mounted upon a base 25 of the press. The piston rod 19 and the connected pull rod 13 are normally urged upwardly through the force of a compression spring 26 to normally cause the clutch to be in its inoperative position.

It is not believed necessary to describe the structure of the press and its clutch in detail, it being understood that, upon tripping and operation of the one-revolution clutch 12, it will connect the driving means, including the flywheel 11 and the crank drive shaft, with a tool support 27 to move the latter, with a selected tool 28 mounted therein, through a complete cycle of operation from its upper position, through the material working portion of its cycle and back to its normal or upper position. A die 30, carried by a die block 31, mounted upon a bed plate 32, is positioned beneath the tool 28 to cooperate therewith when a material or article 33 is fed to the die. The area, where work is performed upon the material or article 33, through the aid of the tool 28 and the die 30, may be called the working position of the press. Into this position, it is generally necessary for one or both of the operator's hands to move to position the material or article 33 and oftentimes to remove the worked material or article from the press. To assure that an operator's hand or hands will not be positioned in this working area when the clutch 12 is tripped or set in operation is the purpose of the electric two-hand safety control arrangement of this invention, which will now be described.

Attached, as indicated in Fig. 1 at 34, to the bed plate 32 of the press, one at each end thereof, are a pair of normally operable double push buttons or electric circuit controlling switches 36 and 37. The spaced switches 36 and 37, as shown, face the front of the punch press where the operator is positioned, but it will be obvious that they may be mounted to face 90° therefrom or parallel to the opposite end faces of the bed plate

32. The switches 36 and 37 are so positioned that the operator may conveniently reach and actuate them, but the safety control arrangement is such that the use of both hands is required to initiate each cycle of operation of the press. Also mounted upon the base 25 of the press adjacent the air cylinder unit 20, by means of a bracket 38, is a conventional type solenoid controlled spring returned air valve 39 for controlling the passage of air under pressure, supplied by an air supply line 40 to the valve from a suitable source, to the air cylinder unit by an air line 41. An exhaust air line for the cylinder unit 20 and air valve 39 is indicated at 43 on the valve. When air is admitted to the cylinder unit 20 through the air valve 39, the piston rod 19 is moved downwardly and through the previously described connections the clutch 12 is tripped to initiate a single cycle of operation of the press. When the supply of air under pressure is cut off from the cylinder unit 20 by the air valve 39, the spring 26 acts to move the piston rod 19 upwardly and thus return the clutch tripping elements to their inoperative positions, which permits the clutch 12 to return to its normal inoperative position, thereby disengaging the flywheel 11 from the crank drive shaft of the press. As the piston rod 19 of the cylinder unit 20 moves upwardly and air through the valve 39 is cut off from the cylinder unit through the air line 41, the cylinder unit and air valve are exhausted through the air line 43.

In the operation of the electric two-hand safety control arrangement, the clutch 12 will be held inoperative to connect the flywheel 11, with the crank drive shaft of the press when the switches 36 and 37 are permitted to move to their normal out positions, as shown in the drawing, when the operator removes his hands therefrom, as will be apparent by consideration of the following description of the mode of operation of the control arrangement, taken in conjunction with Fig. 2, which is a diagrammatic view illustrating an electric circuit for controlling the actuation of the clutch 12. With the switches 36 and 37 in their out positions, as just described, and assuming that a main switch 44 is closed, current will be supplied from one side of a 110 volt source 45 through bridged stationary contacts 50, 51, 52 and 53 of the switches 36 and 37, through an electromagnet 54 of a suitable mechanical latching electrical reset relay 55 and back to the other side of the 110 volt source 45. The electromagnet 54 is thus energized and maintains a mechanical latch 58 of the relay 55 out of engagement with a contact lever 59 of the relay 55.

To initiate a single cycle of operation of the punch press 10, the operator must push simultaneously on each of the switches 36 and 37, using both hands, one on each of the switches, and in so doing, stationary contacts 60, 61, 62 and 63 of the switches are bridged, whereupon current will be supplied therethrough to the relay 55, which is energized and pulls its contact lever 59 into position with its contact 67 to close a circuit to an electronic timer 68. Simultaneously with the energization of the relay 55, the circuit, through the electromagnet 54, is broken, and it becomes deenergized and releases the latch 58, whereupon it moves into latching engagement with the contact lever 59 of the relay 55 under the urging of a connected tension spring 69.

The electronic timer 68, which may be any suitable timer, is capable, upon initiation of opera-

tion, to immediately close a contact pair 70 and hold them closed for a predetermined interval of time and then open. Means included in the timer is provided for varying the timing interval. 5 It is to be understood that the timer 68, after being set in operation in the manner described, will remain in operation for the predetermined set period of time and will not repeat until it receives a new impulse through a resetting of the 10 mechanical latching relay 55. Upon closure of the contact pair 70, current will be supplied to a normally open relay 71, which is energized and pulls its contact lever 14 into position with its contact 75 to close a circuit to a solenoid 76, 15 which has a movable core 77. The closure of the latter circuit moves the core 77 upwardly and since it is operatively connected to a movable spring returned element 78 of the valve 39, which controls the supply of air under pressure through the valve to the cylinder unit 20, the pull rod 13 is moved downwardly and the clutch 12 is thus tripped and a single cycle of operation of the press is initiated. The energizing circuit to the solenoid 76 remains closed until the predetermined interval of time controlled by the timer 68 runs out and such interval of time will agree with the time necessary to complete a single operation of the press.

20 30 To cause the timer 68 to function again, whereby another cycle of operation of the press may be effected, the timer must receive a new impulse and this cannot be completed until the operator releases both switches 36 and 37, thereby causing the circuit to be closed again through the stationary contacts 50, 51, 52 and 53, thus energizing the electromagnet 54 which pulls back the latch 58 and releases contact lever 59 of the relay 55, which, at the same time, is deenergized, 35 40 the contact lever opening the circuit to the timer 68 at its contact 67, and conditioning it to again receive an impulse. The safety control arrangement has now been returned to its normal condition and another impulse to the timer 68 can now be made to cause another cycle of operation of the press by the operator again using both hands to push the switches 36 and 37 to again bridge the stationary contacts 60, 61, 62 and 63 and thereby, in the manner previously described, 45 50 to cause the timer 68 to receive another impulse, which results in another cycle of operation of the press.

55 It is to be understood that the above-described arrangements are simply illustrative of the application of the principles of the invention. Numerous other arrangements may be readily devised by those skilled in the art which will embody the principles of the invention and fall 60 within the spirit and scope thereof.

What is claimed is:

A device for controlling the current to a load comprising a source of current, a timer connected to said source and operable upon the completion of an auxiliary circuit thereto to close a contact pair of the timer and maintain them closed for a predetermined interval, said contact pair having one contact connected to one side of said source, a relay having one side of its winding connected to the other side of said source and having the other side of its winding connected to the other contact of said contact pair, a latch actuating electromagnet having one side of its winding connected to said one side of said source 65 70 and the other side of its winding normally connected to said one side of said source

nected through a pair of manually operated switches connected in series to the other side of said source, and a second relay having its armature positioned to be latched by the latch actuating electromagnet when said electromagnet is deenergized, said second relay having one side of its winding connected to said one side of said source and having the other side of its winding connectible in series to said switches in their off-normal or operative positions to the other side of said source, said auxiliary circuit being under control of said second relay for closing said contact pair to initiate the operation of the timer whereby actuation of both of said switches is necessary to render the latch-actuating elec- 10
15

both of said switches is necessary before another cycle of operation can be initiated.
